UNITED STATES PATENT OFFICE

JAMES J. HENNESSY, OF NEW YORK, N. Y.

LUBRICATOR

Application filed March 12, 1928. Serial No. 261,015.

My invention relates to lubricators adapted to be applied to the axle journals of railway rolling stock, and particularly designed with reference to application to A. R. A. journal boxes.

The main object of my invention is to provide a lubricator which may be readily inserted in a standard A. R. A. box without any change in or machining of the latter.

More detailed objects are to maintain the lubricating device in proper position in the box; to provide an efficient economical simple pump structure which will be operated by the shifting of the axle back and forth lengthwise of the box; which will permit the packing of the journal with cotton waste in the usual manner; and which will permit the box to be jacked up, for the removal of the bearing brass, without injury to the lubricator.

In Patent No. 1,444,461, issued to me February 6, 1923 and Patent No. 1,514,855, issued to me November 11, 1924 I illustrate journal lubricators intended for the same general purpose but involving more complicated structures.

In the accompanying drawings which illustrate a selected embodiment of my invention—

Figure 1 is a vertical longitudinal section through the lower portion of the journal box to which my lubricator is applied and illustrating the adjacent portion of the journal in elevation.

Figure 2 is a top view of my lubricator, the adjacent portions of the box being sectioned.

Figures 3 and 4 are vertical transverse sections taken on lines 3—3 and 4—4 of Figure 1.

The journal A is of standard form and mounts a journal box B also of A. R. A. standard construction and provided with spaced walls C for receiving a dust guard (not shown) of any approved form.

The lubricator includes a body 1 provided with legs 2 for resting upon the bottom wall of the box B and also including a pump cylinder chamber 3, the larger portion of which is inclined upwardly and outwardly toward the outer end of the device and the corresponding end of the journal A. A pump

plunger or piston 4 is slidably mounted in cylinder 3 and projects beyond the same, terminating in an enlarged head 5. A coiled spring 6, seated in a suitable recess in body 1, yieldingly thrusts plunger 4 outwardly. Ears 7 project from the outer end of body 1 and form spaced bearings for a pin 8 upon which a bell crank 9 is pivoted. The upper arm 10 of the bell crank engages the lower outer face of the journal A and the lower arm 11 of the bell crank terminates in a cam surface which engages the head 5 of the pump plunger.

Obviously movement of the journal A to the left will rotate bell crank 9 so as to force plunger 4 inwardly of the pump cylinder and movement of the journal A to the right will permit spring 6 to thrust the pump plunger outwardly.

The pump cylinder has an inlet opening 12 and a discharge opening 13, each equipped with a ball check valve 14. It will be understood that lubricant is supplied to the lower portion of the box to a level above inlet opening 12 and that this lubricant will be drawn into the pump chamber 3 when plunger 4 moves to the left and will be forced upwardly through discharge outlet 13 when plunger 4 is moved to the right. The rear end of body 1 is enlarged as indicated at 1^a and a screen 80 is provided over the bottom of this enlarged portion to exclude cotton fibers or other dirt from being drawn into the pump chamber. The enlarged screen area facilitates admission of oil to the pump and provides for longer operation than would be possible if the inlet opening were restricted and thereby likely to be more quickly clogged with dirt.

A conduit 15 is formed on the top of body 1 and a conduit extension 16 is slidably mounted in conduit 15 and includes a shouldered portion 17 extending outwardly beyond the top of conduit 15. A spring 18 yieldingly supports extension 16 and serves to thrust the same against the surface of the journal 95 to which the device is applied.

A suitable pin and slot arrangement as indicated at 19 limits the outward movement of extension 16 so that the same will not be disassembled from the remainder of the lu- 100

bricator structure when the device is not applied to a journal.

Spaced from conduit 15 is an upstanding rib or lug 20, the height of which is greater than the overall height of conduit 15 and extension 16 when the latter is depressed to the point where its shoulder 17 rests on the top of conduit 15. The function of lug 20 is to engage the underside of the journal A, when the box is jacked up to remove the bearing brass, and thereby avoid injury to the more delicate moving parts of the lubricator.

A screen 21 is provided with a suitable opening for fitting over the lubricator body and the lubricator body has shoulders 22 formed on its sides for supporting screen 21 as shown. Screen 21 extends outwardly from the lubricator body until it contacts with an upwardly extending surface of the box B and serves as a support for waste W with which the box will be packed in the usual manner.

The lubricator will pump lubricant to the surface of the journal keeping the lower portion of the same moist and avoiding the glazed area of the waste which is prevalent in ordinary boxes. Surplus lubricant will drain back through the waste to the bottom of the box and the waste will distribute lubricant to a large surface of the journal by capillary attraction in the usual manner.

The rear end of screen 21 includes an inverted U-shaped flange 23 fitted over the inner dust guard wall C and serving to hold the screen and lubricator body in desired position irrespective of any jars or other forces tending to shift the lubricator.

Obviously many of the details of my invention may be varied and some of the features may be eliminated without departing from the spirit of my invention, and I contemplate the exclusive use of all such modifications of my invention as come within the scope of my claims.

45 I claim:

1. In combination, a railway car journal, a journal box mounted thereon and having a horizontal bottom wall curved upwardly at its outer end, a removable lubricating device mounted on the bottom of said box and including a pump chamber and straight plunger inclined upwardly from the bottom of said box toward the outer end of said journal, and a single rigid bell crank fulcrumed on the wall of said chamber over the curved portion of said wall and contacting directly with the end of said plunger and directly with the lower outer edge of said journal for operating said plunger as said journal reciprocates in said box.

2. In a lubricator of the class described, a member adapted to rest on the bottom of a journal box, a pump chamber in said member, a conduit on said member leading upwardly from said chamber, a conduit exten-

sion telescopingly assembled with said conduit and projecting above the same and adapted to yieldingly engage the bottom of a journal to be lubricated, and an upright rigid element on said member for engaging said journal and limiting the approach of the bottom of said box toward said journal to protect the moving elements of the lubricator when the box is jacked up to apply or remove its bearing on said journal.

3. In combination, a railway car journal, a journal box mounted thereon, a journal lubricator in the bottom of said box and including an upstanding conduit element, a spring surrounding said element, a conduit extension slidably fitting in said element with a shoulder extending outwardly over the top thereof and over said spring, and a rigid rib or lug spaced from said element and extending above the level of the top of said extension when the latter is moved downwardly so that its shoulder engages the top of said element.

4. In combination, a railway car journal box having a dust guard positioning rib, a pump body member adapted to rest upon the bottom of the box and spaced from the front end of said box, and a waste supporting screen fitting over said body member and having an inverted U-shaped flange fitting over said rib to position said member longitudinally of the box.

5. In a lubricator for application to a railway car journal and a journal box provided with a horizontal bottom wall curved upwardly at its outer end, a removable pump body adapted to rest upon the horizontal portion of said bottom wall and provided with a pump chamber inclined upwardly toward the outer end of said body, a straight pump plunger in said chamber, and a bell crank pivoted on said body and having one leg adapted to contact with the outer end of said journal and having another leg provided with a cam terminal adapted to contact with the outer end of said plunger to operate said plunger as said journal shifts axially within said box.

6. In a lubricator for application to a railway car journal and a journal box provided with a horizontal bottom wall curved upwardly at its outer end, a removable pump body adapted to rest upon the horizontal portion of said bottom wall and provided with a pump chamber inclined upwardly toward the outer end of said body, a straight pump plunger in said chamber, and a member pivoted on said body and having contact with the end of said journal and the end of said plunger to reciprocate said plunger as said journal shifts axially within said box.

7. In a lubricator of the class described, a long narrow body having a pump chamber formed therein, a discharge conduit leading upwardly from an intermediate portion

of said chamber, a conduit extension telescopingly assembled with said conduit, means for yieldingly projecting said extension above said conduit, the inner end of said body being widened to rest on substantially spaced points on the bottom of the journal box to which the lubricator is applied, and an upstanding rib extending across said widened end to limit the approach of said box towards said journal.

10 8. In a lubricator of the class described, a long narrow body having a pump chamber formed therein, a discharge conduit leading upwardly from an intermediate portion 15 of said chamber, a conduit extension telescopingly assembled with said conduit, means for yieldingly projecting said extension above said conduit, a portion of said body being widened to engage substantially spaced points on the bottom of the journal 20 to which the lubricator is applied, and an upstanding rib extending across said widened portion to limit the approach of said box towards said journal.

25 In testimony whereof I hereunto affix my signature this 7th day of March, 1928.

JAS. J. HENNESSY.
